Primary Examiner — Barbara Fox*Assistant Examiner* — Kimberly Barnes(74) *Attorney, Agent, or Firm* — Chris J. Katopis**CLAIM**

The ornamental design for a display screen with soccer keyboard graphical user interface, as shown and described.

DESCRIPTION

The FIGURE is a front view of a display screen with keyboard graphical user interface showing the new design.

The broken lines shown in the drawing illustrate portions of the display screen with soccer keyboard graphical user interface that form no part of the claimed design.
